TOOTHBRUSH

Filed March 11, 1929

Thomas S. Butler, INVENTOR
BY *Victor J. Evans*
HIS ATTORNEY

UNITED STATES PATENT OFFICE

THOMAS S. BUTLER, OF CHICAGO, ILLINOIS

TOOTHBRUSH

Application filed March 11, 1929. Serial No. 346,150.

This invention relates to certain novel improvements in tooth brushes and has for its principal object the provision of an improved construction of this character which will be highly efficient in use and economical in manufacture.

The salient object of my invention is to provide a tooth brush structure which will be so arranged in a manner that it will be effective in cleaning both sides of the teeth at one operation.

Another object of the invention, ancillary to the foregoing, is to provide a structure in which means will be provided for facilitating the manipulation of a brush of the above described type.

Another object of the invention is to provide a brush of the above named character which will embody an arrangement whereby the cleaning preparation intended to be used with the brush may be so arranged in the handle thereof that it may be expeditiously forced onto the bristles of the brush when so desired.

A still further object of the invention is to provide an arrangement for the brush structure in which the bristles may be so arranged that they may be expeditiously removed when so desired.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is an elevational view depicting a preferred form of construction for my device;

Fig. 2 is a plan view of the device in operative position;

Fig. 3 is a fragmental view partly in elevation and partly in section of the upper end of the mechanisms illustrated in Fig. 1, said view being drawn to an enlarged scale;

Fig. 4 is a fragmental plan view of the mechanisms as illustrated in Fig. 3;

Fig. 5 is a vertical sectional view of the handle member employed in the device;

Fig. 6 is a sectional detail view taken substantially on the line 6—6 on Fig. 4;

Fig. 7 is a detail view of the cartridge which contains a cleaning preparation that is intended to be mounted in the handle structure; and

Fig. 8 is a detail view of the connection between the bristle bearing portion of my improved brush structure and the handle member.

In the accompanying drawings wherein I have illustrated the preferred form of construction for my device 10 indicates a tubular body member which forms the handle of my improved construction. One end of this body member is rounded as indicated at 11 and a nozzle 12 projects from this rounded end portion at right angles with respect to the axis of the cylindrical body 10. The opposite end of the cylindrical body 10 is closed by a removable cap 13 which in the present instance is screw threaded onto the body 10.

The tubular body 10 is adapted to receive a cartridge 14 in which a cleaning substance such as a suitable paste is housed and this cartridge 14 is inserted into the tubular body member 10 so that the forward end thereof will be disposed adjacent the rounded end 11. An annular disc 15 is disposed in the tubular body 10 and has a rod 16 extending therefrom interiorly of the tubular body member 10 and this rod 16 is preferably disposed on the axis of said body. At the inner end of the rod 16 is a piston 17 which rides on the inner surface of the cartridge 14.

Projecting from the disc 15 is a lug 19 which extends through a slot 18 formed in the tubular body 10. This lug 19 is so engaged that the disc 15 may be moved toward the rounded end portion 11 which will force the material from the cartridge 14 through the nozzle 12.

A tab portion 19 is directed from the cartridge 14 and has the free end thereof extended toward the end of the cartridge 95 which is inserted toward the rounded end 11. After the piston 17 has been forced beyond this tab 19 the tab springs back so that when the piston 17 is moved toward the cap 13 said piston will engage the free end of the 100

tab 19 and thus the cartridge 14 will move with the piston 17 and in this manner the cartridge 14 may be expeditiously removed from the tubular body 10 after the same has 5 been emptied.

A substantially U-shape bracket 20 is provided which includes arms 21 and 22. The arm 22 has an offset portion adjacent the outer end which is indicated by 23. The 10 outer ends of the arms 21 and 22 have enlarged portions 24, the purpose of which will be set forth presently.

I provide two bristle bearing heads 25 and 26 which are mounted in housings 27 and 15 28. The housings 27 and 28 are substantially rectangular in cross-section and have a slot 29 formed in one face thereof as clearly illustrated in Fig. 6 through which the bristles 30 may extend. In the bristle 20 bearing heads I provide openings 31 and the bristles 30 are projected into these openings and are engaged by spring members 32 which retains the bristles in these heads. When the bristles become worn they may be 25 extracted from the openings 31 and from engagement with the spring members 32 and new bristles may be inserted.

The enlarged end portions on the ends 30 of the arms 21 and 22 are inserted into the housings 27 and 28. The enlarged end portion 24 on the arm 22 is inserted into the housing 27 and is disposed therein between the wall portion of the housing 27 opposite the wall portion having the slot 29 therein 35 and the back of the bristle bearing head 25 as clearly illustrated in Figs. 3, 4 and 6. On the enlarged end portion 24 are outwardly extending detents 33 and 34 which fit into openings 35 and 36 in the wall portion 40 of the housing 27 having the opening 29 formed therein and these arms serve to lock the bristle bearing head 25 in the housing 27, this end of the housing being open to permit the insertion of the bristle bearing head 25 while the opposite end thereof is closed. The bristle bearing head 26 is similarly mounted in the housing 28 and it is apparent from the Fig. 2 that the bristles of these two brush constructions are 45 arranged to extend toward each other.

The bight-portion 37 of the U-shape bracket 20 is intended to be disposed in a link 38 having an opening 39 therein. This link 38 may be formed of any suitable material and in this connection a preferred material is metal which may be covered with a suitable resilient material such as rubber. The opening 39 permits the bight-portion 55 37 of the bracket 20 to be moved relative to the member 38 and also permits the bracket 20 to be pivoted about this member.

In the offset portion 23 of the arm 22 I provide an opening 40 having a keyway 41 associated therewith. On the nozzle 12 I 60 provide a boss 42. The nozzle 12 is passed

through the opening 41 and the lug 42 is passed through the keyway 41 so that this lug will be disposed beyond the portion 23 and in this manner the bracket 20 is connected to the tubular body member 10.

In use, the link 38 is disposed between the teeth of the upper and lower jaw with the slot 39 opening horizontally. For example, if the link 38 was disposed between the bicuspid teeth of the right side of the jaw 75 the bristles 30 of the heads 25 and 26 would be disposed on the inner and outer sides, respectively, of the teeth adjacent the eye or canine teeth on the left side of the jaw, these bristles being associated with either 80 the teeth on the upper or lower jaw. The jaw 10 would then be gripped and in this manner the bristles 30 might be moved either vertically or laterally thereover dependent upon the manipulation 85 of the body 10. In order to clean the teeth rearwardly of the just described teeth the link 38 would be gradually moved forwardly thus permitting the bristles to be moved further rearwardly and when desired to clean 90 teeth forwardly of the described teeth the link 38 would be moved rearwardly. When desired to clean the teeth where the link 38 has been gripped the same would be 95 moved into a position whereby it could be gripped by the previously cleaned teeth and the above described action would again be repeated. Since the link 38 is gripped between the teeth with the opening 39 opening 100 horizontally it is manifest that the arms 21 and 22 and the bight portion 37 may be moved between the teeth through the opening 39 and may also be pivoted vertically relative to the teeth and therefore the above 105 described cleaning action may be carried out.

The nozzle 12 includes a discharge portion 43 which extends to a point in juxtaposition to the inner end of the bristle bearing heads and by manipulating the lug 17 in the manner set forth the cleaning preparation in the cartridge 14 may be forced out onto the bristles so as to aid the cleaning action hereinbefore described.

It is apparent that the link 38 will be disposed at different points in the jaw so as the bristles may act on different teeth and this moving about is carried on until all of the teeth have been cleaned.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what 130

I claim as new and desire to protect by Letters Patent is:

1. In a device of the class described, a bracket member having brush structures mounted at the outer ends thereof having the bristles extending toward each other, a handle member connected to said bracket member whereby vertical and horizontal movement may be imparted to said bracket member and said brush structures, said bracket member having a portion thereof disposed in a member having elongated openings formed therein whereby when said last named member is held stationary and said vertical movement is imparted to said bracket member said bracket member is pivoted about said stationary member and when said horizontal movement is imparted to said bracket member said bracket member is moved through said elongated slot.
2. In a device of the class described, a substantially U-shape bracket member having brush structures mounted at the outer ends of the arms thereof, said bracket member having the bight-portion thereof confined in an elongated opening in a link member, and a handle structure adapted to be connected to one of the arms of said bracket structure whereby vertical and horizontal movement may be imparted thereto.
3. In a device of the class described, a substantially U-shape bracket member having brush structures mounted at the outer ends of the arms thereof, said bracket member having the bight-portion thereof confined in an elongated opening in a link member, and a handle structure connected to one of the arms of said bracket structure whereby vertical and horizontal movement may be imparted thereto, said handle member containing a cleaning preparation contained in a cartridge, a nozzle on said handle member extending to a point in juxtaposition to the bristles of said brush structure, and means for forcing material from said cartridge through said nozzle onto said brush structures.

In testimony whereof I affix my signature.
THOMAS S. BUTLER.
